P. H. Letchford

UNITED STATES PATENT OFFICE

PERCY H. LETCHFORD, OF WINNIPEG, MANITOBA, CANADA

HEEL FOR BOOTS OR SHOES

Application filed December 1, 1927. Serial No. 237,082.

The invention relates to improvements in heels for boots or shoes and an object of the invention is to provide a unitary rubber heel adapted to be attached as a unit to the boot or shoe and which is arranged so that it can be easily and effectively fastened to the boot or shoe and which is constructed so that it presents a tread face as ordinarily employed in rubber heels and having the desirable wearing qualities and an inner layer or portion of softer and more resilient rubber, such structure providing a heel which will wear for a considerable period and will absorb to a marked degree the jar occasioned in walking.

A further object of the invention is to construct a rubber heel of the above type which embodies suitably located nail holes passing through the hard rubber layer and into the soft rubber layer and retaining washers at the inner ends of the holes imbedded in the soft rubber layer and of such dimension that they effectively anchor the heads of the nails utilized for securing the rubber heel to the boot or shoe.

A further object is to construct a rubber heel having the aforementioned features which can be readily manufactured by those familiar with the handling of rubber.

With the above more important objects in view, the invention consists essentially in the arrangement and construction of parts hereinafter more particularly described, reference being had to the accompanying drawing, in which:

Fig. 1 is a side view of a shoe fitted with my rubber heel.

Fig. 2 is an enlarged detailed vertical sectional view longitudinally through the heel, the section passing centrally through two of the nail admitting holes.

Fig. 3 is a vertical sectional view of the rubber heel as it appears in Figure 2 and with the nails omitted.

Fig. 4 is a perspective view of the heel.

In the drawing like characters of reference indicate corresponding parts in the several figures.

The rubber heels at present found on the market are as far as I am aware made from

a relatively hard rubber, the rubber being of the same consistency throughout the entire heel. The tread face of the rubber heel obviously requires to withstand the constant wear to which it is subjected and accordingly has to be relatively hard and as the rubber is of the same consistency throughout, the shock absorbing qualities of the heel are materially reduced.

The heel which I provide is of the customary shape and presents a rubber tread face of sufficient hardness to effectively withstand the wear to which a heel is subjected and between this tread face and the shoe, I introduce a layer of rubber having desirable resilient qualities so that the heel as a whole will wear a considerable time and possesses a cushioning effect very desirable to the wearer.

The heel embodies an outer tread layer or portion 1 of wear resisting rubber as ordinarily employed in rubber heels and an inner layer or portion 2 of softer and more resilient rubber, the two layers being firmly bonded together. The layer 1 is made so that it will withstand the wear to which it is subjected whilst the layer 2 provides a cushioning effect which is very desirable as it absorbs the shock to which the heel is subjected.

Nail holes 3 are provided in the heel, these nail holes passing entirely through the outer tread layer and into the soft layer and at the inner ends of the nail holes, there are relatively small pockets 4. Washers 5 are imbedded in the relatively soft rubber layer 2 at the upper ends of the holes 3, the washers being provided with central openings 6 to receive the customary fastening nails later described and being of sufficient size to effectively anchor the nails.

When the heel is in the course of making, the two layers of rubber which are initially of a putty-like consistency are cemented together and they are then cut by a suitable die to simulate the shape of a heel. The heel then provided is placed in a closed mould where it is pressed into the finished heel shape. The bottom part of the mould is provided with upstanding moulding pins

having contracted extensions at their upper ends which pins form the nail holes 3 and the pockets 4 hereinbefore mentioned. The shoulders provided by the contracted upper ends of the pins serve to support the washers 5 at their proper height within the heel and as the rubber is at this time of a putty-like consistency and is placed in the mould under pressure, the rubber moulds around the pins and the washers and so imbeds the washers in the position shown in the drawing.

10 The mould containing the heel is heated in the usual manner to vulcanize the rubber and 15 the heel when withdrawn from the mould presents the relatively soft resilient rubber layer 2 and the relatively hard wear resisting rubber layer 1 and has the washers 20 5 imbedded in the layer 2 and the nail holes 3 leading to the washers, the nail holes being of less diameter than the exterior diameter of the washers.

25 I have placed a dotted line A—A' on the drawing Figure 3 and in the completed heel, that part above the dotted line is a relatively soft resilient rubber whilst that below the dotted line is relatively hard wear resisting rubber.

30 When the heel is to be attached as a unit to the customary leather layers 7 of the heel of the shoe 8, the rubber heel is placed on the heel layers and evened up with the same and the nails 9 are passed through the holes 3 and through those 6 of the washers and are 35 driven home to the position shown in Figure 2. As the nails engage the washers which are firmly anchored in the inner layer of the rubber heel, they effectively hold the heel to the shoe and they do not in any way 40 interfere with the resilient qualities of the heel.

What I claim as my invention is:—

45 A unitary rubber heel, adapted to be attached as a unit to a shoe, comprising an outer layer of comparatively hard rubber and an inner layer of comparatively soft cushioning rubber, there being suitably disposed nail holes passing through the outer layer and into the inner layer and terminating 50 below the upper surface of the inner layer, and anchoring nail receiving washers wholly imbedded in the soft rubber layer and situated at the upper ends of the holes.

55 Signed at Winnipeg this 5th day of November, 1927.

PERCY H. LETCHFORD.
